Attorney

UNITED STATES PATENT OFFICE

ALLEN T. LONG, OF PETERSBURG, VIRGINIA, ASSIGNOR TO ATKINSON & LONG MFG. CO.,
OF PETERSBURG, VIRGINIA, A CORPORATION OF NEW JERSEY

LOCK

Application filed February 28, 1931. Serial No. 519,189.

This invention relates to locks, particularly locks for traveling bags, satchels and the like, though the invention is not necessarily limited thereto.

5 The general object of the invention is to provide a construction wherein the hasp when closed will entirely cover over the rivets which attach the base of the lock to the body of the bag, trunk or other receptacle.

10 A further object is to provide a lock of this character having a hinge of such construction that the hinge is so covered and protected that the lock cannot be readily broken at the hinge or the pintle of the hinge cut through.

15 Other objects will appear in the course of the following description.

My invention is illustrated in the accompanying drawings, wherein:—

Figure 1 is a side elevation of a lock constructed in accordance with my invention;

Figure 2 is a face view thereof;

Figure 3 is a side elevation broken away;

Figure 4 is a front elevation with the hasp raised.

25 Referring to these drawings, 10 designates the base for the hasp, which base is formed at its upper end with a slightly depressed or transversely concave portion 11 and with two ears 12 extending upward or outward from this concave portion of the base. This base is held to the bag or trunk section or other section of the receptacle by means of rivets 13. Mounted upon this base is a hasp designated 14, this hasp being formed to provide 30 a bead 15, the bead being approximately semi-circular in cross section. The ends of the bead are formed to provide the inwardly extending ears 16 which overlap the exterior faces of the ears 12. A pintle 17 passes through these ears and is, of course, headed at its extremities. A spring 18 surrounds this pintle and is disposed between the ears 12, this spring having one end bearing 35 against the base 10 and the other end bearing against the inside face of the hasp 14. Thus it will be seen that the spring acts to urge the lid upward to a raised position.

The bead of the hasp is slotted at 28 to accommodate the ears 12 and the end walls of these slots when the hasp is turned outward

engage the edges of the ears which thus act as stops limiting the upward movement of the hasp. The inside face of the hasp carries upon it the two keepers 19 having beveled faces. The lock plate 20 is attached by rivets 55 21 to the bag or other member and this lock plate is provided with the slots 22 for the reception of the keepers 19.

Operating on the inside face of the lock plate are the bolts 23 which are spring projected. These bolts are connected to a slide 24 mounted upon the lower end of the lock plate, this slide having the rotatable locking barrel 26 which is to be key-operated so that the bolts 23 may be projected into the keepers 19 or retracted therefrom. When so projected, the slide 24 which is formed upon its lower edge with a flange 27 whereby it may be operated is held from movement, but when the key is turned to unlock the slide 24, a 70 downward movement of the slide will retract the bolts from engagement with the keepers 19.

It is to be particularly noted that when the hasp 14 is turned down into locking position, 75 that the hasp covers the rivets 13 and the rivets 21 and that the edge of the hasp comes flush with the upper edge of the slide 24. It is also to be noted that when the hasp is closed, the pintle except at its ends, and the 80 springs surrounding the pintle are entirely enclosed within the bead 15 and that the ears 12, except as to the edges of the ears, are also disposed within the bead 15, the slots 28 which accommodate the ears 12 being of approximately the same width as the thickness 85 of the ears and being practically closed by the peripheries of the ears 12. Thus it will be seen that the hasp completely covers the rivets which are used to fasten the lock to the case and almost completely covers the hinge and thus makes the lock practically a 90 burglar-proof lock.

While I have shown a preferable form of construction, I do not wish to be limited to the exact details of construction as it is obvious that these might be changed without departing from the spirit of the invention as defined in the appended claims.

I claim:—

1. A lock comprising a hasp base having rivets attaching it to an article, and having at one end outwardly projecting ears, a hasp 5 as wide as and longer than the base and having ears overlapping and disposed outwardly of the first named ears, a pintle extending through both pairs of ears, the hinge end of the hasp having a bead extending approximately the full length of and extending over the pintle and ears and circumferentially slotted in register with the first named ears, a lock plate having rivets whereby it may be attached to an article, the hasp when closed 10 extending over the rivets of the hasp base and over the lock plate and covering the rivets thereof, the hasp and lock plate having co-acting keepers and bolts.
2. A lock comprising a hasp base having 20 rivets attaching it to an article, and a lock plate having rivets whereby it may be attached to the article, the hasp base at one end having a transversely concave portion having a length equal to the width of the base and 25 having outwardly projecting ears adjacent the ends of this concave portion, a hasp as wide as and longer than the base and having ears at its side edges at one end overlapping the first named ears and disposed exteriorly 30 thereof, a pintle extending through both pairs of ears, a coiled contractile spring surrounding the pintle and bearing against the base and hasp respectively to urge the hasp in open position, the hinge end of the hasp 35 having a bead approximately equal in length to and extending over the pintle, the spring and said ears, the bead being circumferentially slotted in register with the first-named ears, the lock plate and hasp having coacting 40 keepers and bolts.

In testimony whereof I hereunto affix my signature.

ALLEN T. LONG.
